UNITED STATES PATENT OFFICE.

GEORGE S. BENJAMIN, OF DETROIT, MICHIGAN.

WINDOW CONSTRUCTION.

1,384,935.

Specification of Letters Patent. Patented July 19, 1921.

Application filed July 24, 1920. Serial No. 298,759.

To all whom it may concern:

Be it known that I, GEORGE S. BENJAMIN, a citizen of the United States, residing at Detroit, in the county of Wayne and State 5 of Michigan, have invented a new and useful Window Construction, of which the following is a specification.

This invention relates to window constructions and more particularly to window constructions wherein a sliding sash member is 10 also hinged so that it may be swung inwardly to facilitate cleaning.

It is an object of the invention to provide a window of the described character having 15 two sliding sashes which are adapted to both be swung inwardly on suitable hinges without interfering one with the other; and it is a further object to provide for effecting such an adjustment of the sashes while both are 20 either raised or lowered, or while one is raised and the other lowered.

The invention further consists in various structural features which facilitate manufacture, secure a high degree of strength, 25 and are conducive to ease of operation, ready installation and an attractive appearance.

A preferred embodiment of the invention is illustrated in the accompanying drawings, wherein,

30 Figure 1 is a view in interior elevation of the improved construction, both sashes being shown in their normal closed positions.

Fig. 2 is a cross-sectional view of the same taken on line 2—2 of Fig. 1, the central portions of the sashes being broken away.

Fig. 3 is a vertical sectional view taken upon line 3—3 of Fig. 1.

Fig. 4 is a cross-sectional view cutting the upper sash and showing the lower one in 40 plan, both sashes being shown swung inwardly at right angles to their normal positions.

In these views the reference characters 1 and 2 respectively designate the upper and 45 lower sashes of the window, and 3 and 4 indicate the side jambs of the window frame. The jamb 3 carries within the window opening two adjacent channel-shaped members 5, preferably formed of sheet metal, and extending substantially the full height of the window opening. Any suitable means may be employed to secure said members to the jamb carrying the same, screws 6 being employed for that purpose in the drawings.

55 The channel members 5 are slidably engaged by complementary channel members 7, which

respectively form hinge mountings for the two sashes. The engagement between the complementary channel members is established by flanging the adjoining edges of the same inward and return-bending the flanged edges of one of the members to embrace the flanges of the other. Thus, in the drawings, the members 5 have their edges flanged oppositely inward, as indicated at 8, and the edges of the members 7 are bent to form opposed return-bent flanges 9 loosely embracing the flanges 8. Each sash is mounted upon the corresponding channel member 7 by two vertically spaced hinges 10, both leaves of said hinges being intermediately bent at a right angle. As is clearly shown in Figs. 2 and 4, however, the hinges of the respective sashes are oppositely bent, so that the hinge pintles 11 of the upper sash are 75 offset away from the jamb 3, while the pintles 12 of the lower sash are offset toward said jamb, and lie close adjacent thereto. The advantage of thus bending the hinge leaves so as to oppositely offset the pivotal 80 axes of the two sashes is made readily apparent by Fig. 4, wherein it is seen that both sashes may at the same time occupy positions transverse to the frame of the window without interfering one with the other. 85

A stop strip 13 is secured to the jamb 4 within the window opening and extending the full height of said opening to form a slide guide for the upper sash 1, and to restrain said sash from any outward yielding. The 90 two sashes overlap each other sufficiently, even when in their respective upper and lower limiting positions, to prevent inward swinging of the sash member 1 until the sash 2 has been unlatched. The latch means for 95 the sash 2 consists of a bolt 14, which is best shown in Fig. 2, which bolt is socketed in the side piece of said sash adjacent the jamb 4 and is acted upon within its socket by a coiled spring 15 maintaining it normally engaged at one end with a vertical groove or channel 16 in said jamb. The other end of said bolt projects, as is seen in Fig. 1, sufficiently to be readily grasped to permit disengagement of the bolt from the channel 16 100 when it is desired to swing the sash 2 inward on its hinges. Obviously the described latch arrangement is one which offers no interference to the normal sliding adjustment of the sash 2. 105

Each sash is counterbalanced by a weight 110 suspended from a cord 18, which passes

over a pulley 19 journaled in the upper end of the jamb 3 and is attached to channel member 7 of said sash by an eye bolt 20.

The described construction possesses numerous advantages, primary of which is the adaptability of the two sashes to occupy at the same time their inwardly swung positions shown in Fig. 4. This not only greatly facilitates washing of the window, but also 10 allows a very thorough ventilation to be effected, when desired. In some cases, also, the described adjustment may be utilized to permit large articles to be readily passed into or out of a building through a window opening. Also the use of sheet metal members to slidably mount the channels permits 15 of a very strong yet compact construction

and is favorable to quantity manufacture at low cost.

I claim—

In a window construction, the combination with a frame having a window opening, of a channel member vertically extended upon said frame within said opening and having its edges flanged toward each other, 25 a complementary channel member having its edges flanged toward each other and returnbent to slidably embrace said flanges of the first mentioned channel member, and a sash hinged to said sliding channel member. 30

In testimony whereof I sign this specification.

GEORGE S. BENJAMIN.
